[57] CLAIM

The ornamental design for question and answer cube, as shown and described.

DESCRIPTION

FIG. 1 is a top, front and side perspective view of a question and answer cube, showing my new design; FIG. 2 is a side elevational view thereof, the opposite side being a mirror image;

FIG. 3 is a top plan view thereof;

FIG. 4 is a bottom plan view thereof;

FIG. 5 is a top, front and side elevational view thereof, shown with one element in an alternate position; and, FIG. 6 is a top, front and side perspective view of a second embodiment of the question and answer cube illustrated in FIG. 1.

FIG-1

FIG-2

FIG-3
